DESIGN FOR A TEXTILE FABRIC OR SIMILAR ARTICLE

Irving H. Fishlove, Chicago, Ill.

Application November 19, 1938, Serial No. 81,236

Term of patent 3½ years

To all whom it may concern:

Be it known that I, Irving H. Fishlove, a citizen of the United States, residing at Chicago, in the county of Cook and State of Illinois, have invented a new, original, and ornamental Design for a Textile Fabric or Similar Article, of which the following is a specification, reference being had to the accompanying drawing, forming part thereof.

The figure is a plan view of a sheet of textile fabric, showing my new design.

I claim:

The ornamental design for a textile fabric or similar article, as shown.

IRVING H. FISHLOVE.
